UNITED STATES PATENT OFFICE.

ROBERT S. POTTER, OF GREENWICH, CONNECTICUT, ASSIGNOR TO THE YALE & TOWNE MANUFACTURING COMPANY, OF STAMFORD, CONNECTICUT.

DOOR CLOSER.

Application filed May 1, 1923. Serial No. 635,918.

To all whom it may concern:

Be it known that I, ROBERT S. POTTER, a citizen of the United States, and a resident of Greenwich, in the county of Fairfield and State of Connecticut, have invented certain new and useful Improvements in Door Closers; and I do hereby declare the following to be a full, clear, and exact description of the invention, such as will enable others skilled in the art to which it appertains to make and use the same.

This invention relates to improvements in door closers and particularly to such as employ a coiled spring of flat metal and a spindle which is cooperable with checking means,—one object of the present invention being to so construct and arrange the spring operating and holding means that friction and binding of the parts shall be reduced to a minimum and the wear and loss of power incident to friction shall be obviated.

A further object is to provide a construction in which a balanced drive for the spring shall be obtained, so that binding and cramping of the movable spring-winding elements shall be obviated.

With these and other objects in view, the invention consists in certain novel features of construction and arrangements of parts as hereinafter set forth and pointed out in the claims.

In the accompanying drawings;

Figure 1 is a sectional view of a door check and closer showing an embodiment of my invention;

Figure 2 is a sectional view taken at right angles to Figure 1;

Figure 3 is a plan view, and

Figures 4 to 11 inclusive are views of various details.

In the drawing I have shown a housing 1 in which the closing spring is enclosed and a cylinder 2 disposed at right angles to said housing and made integral therewith. A nut 3 is located at the juncture of the housing and cylinder and is provided with a sleeve or tubular extension 4, in which the spindle 5 of the device has bearing, said spindle extending through the nut 3 and into the cylinder 2. A crank 6 may be secured to the lower end of the spindle and this crank is connected, through the medium of a rod or pitman 7 with a piston 8 in the cylinder.

The housing 1 is closed by a cover 9 provided with a central opening for a sleeve 10 and through this sleeve, the upper end portion of the spindle 5 passes. A portion of the sleeve 10 is made with a reduced external diameter to receive a pawl plate 12 and with an end portion 13 having flattened side portions, to receive a similarly shaped opening in a ratchet wheel 14. A pawl 15 which engages the ratchet wheel is pivoted to the pawl plate 12, and the latter is provided with an arm 16 which normally engages a lug 17 on the housing cover 9. The main arm or lever 18 of the device (which is to be connected with the door frame in a manner well understood in the art) is secured to the upper end of the spindle 5 and is provided with a depending lug 19 in position to cooperate with the arm 16 of the pawl plate 12.

The sleeve 10 constitutes a hub for a spring case 20 which encloses the flat metal coiled spring 21 of the closer. To afford convenient means for effecting connection of the case 20 with the sleeve or hub 10, the top of said case is provided with a central hole having a toothed wall 22 (Fig. 5), which receives an exteriorly toothed portion 23 (Fig. 4) of the sleeve or hub 10. A plate 24 at the lower end of the case 20 serves to provide a bottom bearing for the latter and prevent cramping of the upper bearing afforded by the sleeve or hub 10 in the top of the housing. The spring case 20 is provided with a slot 25 in which the outer end of the spring 21 engages as shown in Figure 1.

The bottom plate 24 of the spring case 20 surrounds the tubular bearing sleeve 4 but is spaced therefrom for the accommodation of the flange 26 of a bottom hook member 27. The inner end of the closer spring 21 is engaged in a groove 28 in a tubular winder member 29, the latter being mounted to turn on the fixed bearing sleeve 4. The tubular winder 29 is provided at its lower end with a lug 30 to engage a lug 31 projecting upwardly from the flange 26 of the hook member 27, and the latter includes an arm 27^a having a depending lug 27^b which enters a slot or recess 31 in the bottom of the housing. By these devices, the inner winder 29 will be prevented from turning when the spring case 20 (which constitutes the outer winder)

is turned to wind the spring during the swing of the main arm or lever when the device is applied to a left hand door.

The inner spring winder is provided at its upper end with lugs 32 and 33,—the former projecting into the winder and the latter projecting laterally therefrom, as shown in Figure 6.

A driver-hock member 34 (Fig. 9) encircles the spindle 5 (Fig. 1) and is provided with inwardly projecting lugs 35, 35, which enter diametrically opposite grooves or recesses 36, 36 in said spindle 5. A lug 37 depends from the member 34 in position to engage the lug 32 in the upper end of the inner winder 29, and said member 34 includes an arm 34^a having a lug 38 diametrically opposite the lug 37 to engage the lug 33 on the winder member 29.

When the closer is applied to a right hand door and the main arm or lever 18 swings to the right during the opening of the door, the spindle 5 will be rotated and motion will be imparted through the member 34 to the inner winder or spring driver 29 to wind the spring 21 from the inside. At such time the outer end of the spring is held from turning by the means provided to prevent the outer winder or driver,—viz, the spring case 20,—from turning, said means including the sleeve or hub 10, pawl plate 12 and the stationary lug 17 on the cover 9. During such operation of the closer, a balanced drive for winding the spring is obtained by the two oppositely disposed lugs 35 on the member 34 coacting with the oppositely disposed grooves 36 in the spindle and the two oppositely disposed driving lugs 37, 38 with the two oppositely disposed lugs 32, 33 on the spring driver or winder 29.

When the device is applied to a left hand door, the main arm 18 will swing to the left during the opening of the door and the lug 19 on the under side of said arm will drive the pawl plate 12 and with it, the ratchet wheel 14, the spring case hub 10, and the spring case or outer winder or driver 20 to wind the spring from the outside. During such operation of the device, the inner winder or driver 29 will be held from turning by connection thereof with the housing in the manner previously explained.

With my improvement, friction and binding of the movable parts employed in effecting the winding of the closer spring either from the inside for a right hand door or from the outside for a left hand door, are reduced to a minimum and the efficiency as well as the longevity of the device will be enhanced.

Having fully described my invention what I claim as new and desire to secure by Letters-Patent, is:—

1. In a door closer, the combination with a housing, a spindle, a fixed bearing member

for the spindle, an arm for connection with a door, connected with said spindle, and a closer spring in the housing, of an inner winder connected with the spring and encircling said fixed bearing member, an outer winder encircling the spring and connected therewith, connections between the inner winder and the spindle, connections between the outer winder and said arm, and means for preventing the turning of one of said winders when the other winder is turned.

2. In a door closer, the combination with a housing, a spindle, an arm for connection with a door, connected with said spindle, and a closer spring in the housing, of an inner winder connected with the spring, an outer winder encircling the spring and connected therewith, connections between the inner winder and the spindle, connections between the outer winder and said arm, the connecting means between the inner winder and the spindle including a member engaging each of said parts at two diametrically opposite points, and means for preventing the turning of one of said winders when the other winder is turned.

3. In a door closer, the combination with a housing, a spindle, an arm connected with said spindle, and a spring in said housing, of an inner winder connected with the inner end of said spring, connections between said inner winder and said spindle, an outer winder attached to the outer end of the spring and including a case enclosing said spring, a hub mounted in the top of the housing, and a plate constituting a bottom bearing member for said case, connections between the hub of said outer winder and said arm, and means for preventing one of said winders from turning when the other winder is turned.

4. In a door closer, the combination with a housing, a spindle mounted therein, an arm connected with said spindle, and a closer spring in said housing, of a winder within said spring and attached thereto, a member interposed between said spindle and winder and engaging both at diametrically opposite points, and means for holding the outer end of the spring from turning.

5. In a door closer, the combination with a housing, a spindle mounted therein, an arm connected with the spindle, and having diametrically opposite recesses, and a closer spring in the housing, of a winder within said spring and provided at its upper end with diametrically opposite lugs, a member interposed between the spindle and winder and having diametrically opposite lugs co-operable with the diametrically opposite lugs on the winder, said member also having diametrically opposite lugs co-operable with the diametrically opposite recesses in the spindle, and means for preventing movement of the outer end of the spring.

6. In a door closer, the combination with a housing, a spindle therein, an arm connected to said spindle, and a spring within the housing, of a winder within the spring and connected with the inner end thereof, connections between said winder and said spindle, said winder having a lug at its lower end, a hook-member below said winder and having a lug cooperable with the lug on the winder, said hook-member having a part entering a part of the housing, an outer winder surrounding the spring and connected with the outer end thereof, and connections between said arm and outer winder whereby winding of the spring from the outside may be effected.

7. In a door closer, the combination with a housing, a spindle mounted therein, an arm connected with said spindle, a closer spring within the housing, and means operable to hold the inner end of said spring

from turning, of winding means for the spring interposed between the outer end of the spring and said arm, said winding means comprising a case surrounding the spring and connected with the outer end thereof, a hub connected with said case and mounted in the top of the housing, a ratchet wheel rotatable with said hub, a pawl plate mounted loosely on the hub and having an arm, a pawl carried by said plate to cooperate with the ratchet wheel, and a lug on said first-mentioned arm for cooperation with the arm of the pawl plate.

In testimony whereof, I have signed this 35
specification in the presence of two sub-
scribing witnesses.

ROBERT S. POTTER.
